UNITED STATES PATENT OFFICE.

BRUNO BLOCH, OF BERLIN, GERMANY, ASSIGNOR TO MERGENTHALER LINOTYPE COMPANY, A CORPORATION OF NEW YORK.

TYPOGRAPHICAL MACHINE.

1,154,166.

Specification of Letters Patent. Patented Sept. 21, 1915.

Application filed December 10, 1913. Serial No. 805,723.

To all whom it may concern:

Be it known that I, BRUNO BLOCH, a subject of the German Emperor, residing at 23 Chausseestrasse, Berlin, N. 4, in the Empire 5 of Germany, have invented new and useful Improvements in Typographical Machines, of which the following is a specification.

The present invention relates to an arrangement, by means of which machines operated manually through a key board, especially matrix composing and line casting machines may be driven at times mechanically by means of a perforated strip. It has already for this purpose, been proposed to 10 release electrical contacts by means of a perforated strip and thus operate upon the keys of matrix composing machines through the mediation of electromagnets. This arrangement however has the disadvantage of being 15 extremely complicated and sensitive and therefore unreliable. According to the present invention a mechanism independent of the machine itself, and controlled by a perforated strip of paper is provided, to be applied at will to the machine so as to effect 20 a mechanical operation of the key mechanisms. It may operate upon any members of the latter.

Referring to the drawing: Figure 1 is a 25 vertical section taken through the key board mechanism of a linotype machine, and showing my invention applied thereto; Fig. 2 is a side elevation, partly broken away, of my improved mechanism; Fig. 3 is a top plan 30 view of the parts shown in Fig. 2; and Fig. 4 is a detail view.

a are the keys by which in the known manner through mediation of the escapement rods *b*, the escapements *c* can be 35 operated.

According to the invention, and in a covering box not shown in the drawing, a series of levers *d* is suitably fulcrumed on the axis *e*, their front ends projecting out of the covering box, so as to be able to engage notches *n* in the escapement rods *b*. Each of these 40 levers *d* has a releasing pin *f*. The perforated strip of paper *g* is passed around a guide roller *k*¹, and over the the pivoted levers *d*, so as to locate its perforations 45 above the releasing pins *f* of the levers. This strip has the width of the key board and is moved intermittently by a pawl and ratchet arrangement *o* operated by a cam *o*¹ 50 on the driving shaft *p* of the machine. The

strip is moved along by the driven roller in the known manner by means of sprocket wheels *q* engaging continuous rows of perforation in the edges of the strip. The levers *d* are pulled upward by the springs *h* so as 55 to bear against the perforated strip. In order to prevent the latter from being pushed away, a counterpart *i* is provided which has holes at the parts opposite the pins *f*, into which holes these pins can enter, if the strip *g* happens to be perforated at a corresponding place. During each advance of the perforated strip *g* all levers *d* are once moved up and down by the cam disks *k* arranged at the opposite ends of the guide 70 roller *k*¹ for the strip. To this end, a suitably-guided bar *m* is provided, extending over the levers *d* and having upwardly projecting studs *m*¹ engaging the toothed shaped cams on the cam disks *k*. 75

The improved mechanism works as follows:—The perforated paper strip advances intermittently to the extent of one section. Each section has a hole in a position to correspond with the letter to be used. During 80 the movement of the strip *g*, all the levers *d* are held out of contact with the perforated strip by the action of the cam disks *k* on the bar *m*. After the advance of the strip *g*, the studs on the bar *m* enter depressions of 85 the cams *k*, so that the levers *d* are able to move upward, and the lever whose pin *f* is then opposite the hole in the strip *g* is raised by the spring *h* to such an extent as to lift the escapement rod *b*. Each escapement rod is formed with a notch *n* of such dimensions 90 as to allow the corresponding lever *d* when not thus released to move under the action of the cams *k* without imparting movement to the rod. 95

The whole casing within which the releasing device is arranged is made so as to be easily affixed to the machine to be operated, so that the machine may at will be changed from a hand machine into an automatic machine. 100

Having described my invention, I declare that what I claim and desire to secure by Letters Patent is:—

1. Alternative perforated strip mechanism 105 for operating a machine fitted to be operated through a manually operated key board, consisting of a perforated strip, means for advancing it with a step by step motion; releasing studs moved toward the said strip 110

after each advance; means for so moving them and causing one of them to pass through the respectively opposite perforation; and means by which the movement of that passing through actuates the respective key mechanism of the machine.

2. Alternative perforated strip mechanism for operating a machine fitted to be operated through a manually operated key board, consisting of a perforated strip; means for advancing it with a step by step motion; releasing studs moved toward the said strip after each advance; means for so moving them and causing one of them to pass through the respectively opposite perforation; means for moving all the studs away from the strip before each advance of the latter; and means by which the movement of that passing through actuates the respective key mechanism of the machine.

3. Alternative perforated strip mechanism for operating a machine fitted to be operated through a manually operated key board, consisting of a perforated strip; means for advancing it with a step by step motion; releasing studs moved toward the said strip after each advance; levers carrying the said studs; means for so moving the said levers and studs and causing one of the studs to pass through the respectively opposite perforation; means by which the respective lever operates the respective member of the key mechanism synchronously with the passage of the stud through the perforation; and means for returning the levers without affecting the unoperated members of the key mechanism.

4. Alternative perforated strip mechanism for operating a machine fitted to be operated through a manually operated key board, consisting of a perforated strip; means for advancing it with a step by step motion; releasing studs moved toward the said strip after each advance; levers carrying the said studs; a frame supporting the said levers and oscillated vertically by the strip feeding means; means for so moving the said levers and studs and causing one of the studs to pass through the respectively opposite perforation; means by which the respective lever operates the respective member of the key mechanism synchronously with the passage of the stud through the perforation; and means for returning the levers without affecting the unoperated members of the key mechanism.

5. In a typographical machine, the combination of a series of escapement actuating devices, a corresponding series of operating members connected therewith and each pro-

vided with a releasing pin, means tending to operate all of the said members simultaneously, and a perforated strip mechanism to coöperate with the releasing pins of the operating members and allow the operation thereby of one or another of the escapement actuating devices according to the location of the perforation in the strip. 65

6. In a typographical machine, the combination of a series of escapement actuating devices, a corresponding series of members tending constantly to operate said devices and each provided with a releasing pin, and a perforated strip mechanism to coöperate with the releasing pins and permit the operation of one or another of the actuating devices by its corresponding operating member, according to the location of the perforation in the strip. 70 75

7. In a typographical machine, the combination of a series of escapement actuating devices, a corresponding series of operating members therefor each provided with a releasing pin, means tending to operate all of said members simultaneously, a perforated strip mechanism to coöperate with the releasing pins and allow one or another of said members to operate the corresponding escapement actuating device, and means for returning the active member to its original 90 position after its operation.

8. In a typographical machine, the combination of a series of escapement actuating devices, a corresponding series of members tending constantly to operate said devices, 95 releasable means for holding the members against operation, and a perforated strip mechanism to control the operation of said members when released by the holding means. 100

9. In a typographical machine, the combination of a series of escapement actuating devices, a corresponding series of operating members therefor each provided with a releasing pin, a perforated strip mechanism 105 movable step by step past the operating members and adapted to coöperate with their releasing pins and permit the operation of one or another of said members, and means for moving said operating members 110 toward and from the strip as it is advanced to subject their releasing pins to the action of the perforated strip.

In witness whereof I have hereunto set my hand in the presence of two witnesses:

BRUNO BLOCH.
